BOTTOM FOR BOILER FURNACES

Arthur J. Boynton, Winnetka, Ill., assignor to
 H. A. Brassert & Company, Chicago, Ill., a corporation of Illinois

Application May 3, 1930. Serial No. 449,386

9 Claims. (Cl. 110—1)

This invention relates to improvements in bottoms for boiler furnaces particularly adapted though not necessarily limited for use, in connection with powdered coal, and one of the objects of the invention is to provide an improved form or construction of bottom and to provide an improved combination and arrangement of certain materials whereby the desired and new and improved results will be obtained.

10 Heretofore, the use of powdered coal has resulted in temperatures sufficiently high to flux the ash and form a slag therefrom, and various forms of furnace bottoms have been devised, some of which contemplate freezing the liquid 15 slag in a hopper bottom either with or without use of a water screen.

The present invention, however, contemplates the use of an improved substantially flat bottom which is used to collect and retain liquid slag 20 and from which it is drained at intervals through a suitable tapping hole.

In such a construction the boiler wall is usually composed of water cooled brick terminating at the lower end in a pipe of large diameter, 25 the piping forming a part of the boiler circulation.

Heretofore it has been customary to construct or build the boiler bottom tight against the walls of the furnace which in some instances have 30 been suspended from above and in others have been carried from supports below, with the result that expansion of the boiler bottom has caused considerable trouble, as upon the first firing of the boiler an initial expansion takes 35 place which results in a pressure being exerted against the walls.

Upon cooling, the boiler does not contract back to its original position and re-expanded to the same extent or dimensions as those formerly 40 taken after heating, but shows an inclination to progressive growth. This inclination is due to the failure of the bottom material to go completely back into place or normal position. On the contrary hair line cracks are formed 45 which result in a sufficient dislocation of adjacent parts to prevent the bottom from obtaining its former cold or normal size.

When the bottom is again heated the effect is to produce a growth greater than the original 50 growth, with the result that a successive enlargement of the bottom occurs which deforms the boiler walls and tends to force them apart at the corners.

In addition to this trouble, difficulty has been 55 experienced with the materials usually employed

for the bottom, and such constructions have formerly included everything from an acid micaschist to basic dolomite. The ash coal when liquid, will flux such materials and destroy the bottom. Various means have been attempted 60 to overcome this difficulty, the most successful of which has been the use of coke braize which does not only inert to fluxing action, but has so little structural strength that the outer strains on the boiler construction are minimized. Such material, however, is not suitable 65 for good or permanent construction and it requires to be backed up by a solid base of masonry which has a tendency to expand against the boiler wall.

It is one of the objects of the present invention to overcome these difficulties and objections and to provide in a furnace of this character a bottom which is entirely separate from the walls thereof and of such dimensions that 75 it may be raised or lowered if desired independently with respect to and without interfering with the construction of the boiler proper.

A further object is to provide in a construction of this character a layer of suitable material 80 immediately inside of the bottom jacket which is capable of expanding and contracting under pressure, and to arrange immediately inside of such material a sectional water cooled casting 85 extending preferably from the top to the bottom of the bottom proper and supported upon a bottom plate.

A further object is to provide in a structure of this character an inclined wall immediately below the vertical boiler wall and to arrange beneath said inclined wall an inclined water cooled 90 surface bolted or otherwise secured to the cast steel or outer jacket of the bottom.

A further object is to provide an improved 95 hearth construction preferably composed of a layer of carbon blocks above, first quality fire clay in an intermediate position and brick or other insulating material below and next to the bottom.

A further object is to provide improved means 100 for forming a water seal construction between the bottom and the walls to prevent the escape of gas and improved means for supplying a cooling liquid to the cooling areas and from them into the water seal from which the liquid 105 will subsequently escape and flow away.

To the attainment of these ends and the accomplishment of other new and useful objects as will appear, the invention consists in the features of novelty in substantially the construction, com- 110

bination and arrangement of the several parts hereinafter more fully described and claimed and shown in the accompanying drawings illustrating this invention, and in which

5 Figure 1 is an enlarged detail sectional view of a portion of the bottom and the adjacent furnace wall, constructed in accordance with the principles of this invention.

Figure 2 is a detail sectional view taken on 10 line 2—2, Figure 3.

Figure 3 is a detail sectional view taken on line 3—3, Figure 2.

Referring more particularly to the drawings, the numeral 10 designates generally the shell of 15 a boiler which is lined with a standard lining or blocks 11, and arranged at the bottom of the walls 10 is a header 12 to which is connected pipes 13 forming a part of the circulating system.

20 The bottom of the boiler consists of a bottom or supporting plate 13^a which is supported by suitable supports 14.

Around the outside of the bottom proper is a casting or shell 15 which is supported by and 25 secured to the bottom plate 13^a by means of suitable fastening devices 16.

Arranged within the casting 15 is a sectional water cooled wall 17 of a height substantially equal to the height of the casting 15 and is 30 spaced from the casing so that a cushioning element 18 constructed of any suitable resiliently yielding material, such as rubber or the like, may be arranged therebetween and will be protected by the water cooled wall 17.

35 The water cooled wall encompasses the hearth proper and the hearth itself is preferably composed of a layer of insulating material 19 such as brick or the like and is arranged within the water cooled wall 17 and rests upon the bottom 40 13^a.

45 Superposed upon the insulating material 19 is a layer of refractory material 20, preferably first-class fire clay brick and the insulating material 19 and the layer 20 may be of any desired thicknesses.

50 Superposed upon the refractory material 20 is a layer 21 preferably carbon blocks and the height of the hearth formed by these superposed layers is equal to the height of the water cooled wall 17 so that the top of the hearth is flush with the top of the wall 17.

55 Supported by the casting 15 and encompassing the bottom, preferably resting upon the top of the wall 17 is an inclined water cooled wall 22, preferably formed of a casting which is secured in position in any suitable manner preferably by being bolted to the casting 15 by means of suitable bolts or fastening devices 23^a.

60 This wall or surface 22 is of any desired height and is spaced below the furnace wall. The interior of the inclined wall 22 has communication with the interior of the water cooled wall 17 in any suitable manner preferably by means of a pipe or passage 23 which is connected by means 65 of another pipe 24 with a passage 25 having communication with the interior 26 of the wall 22, and the wall 22 is provided with an outlet passage 27 which discharges into a receptacle 28 supported in any suitable manner, and from 70 which receptacle 28 leads an overflow pipe 29.

75 Cooling liquid is supplied through a pipe 30 from any suitable source and is delivered into the interior 31 of the water cooled wall 17 and flows therefrom through the pipes 23—24 into the passage 25, and into the space 26 in the wall

22 to be discharged therefrom and through the pipe 27 to be discharged into the receptacle 28.

This receptacle 28 forms a portion of the liquid seal to prevent escape of gas between the bottom and the wall of the furnace.

To that end there is provided a plate or depending member 32 which is secured preferably to the furnace wall in any suitable manner such as by means of a bracket 33.

It will therefore be manifest that the cooling liquid flows successively through the wall 17, wall 22 and into the liquid seal 28.

Supported above the inclined wall 22 is another inclined wall 34 which is arranged below the wall 11 of the furnace and terminates short of and is spaced above the wall 22. The wall 34 is formed in any suitable manner preferably from refractory material and this wall 34 is cooled in any suitable manner such as through the medium of cooling pipes 35.

90 The inclined walls are preferably employed when carbon is used as a bottom on account of the fact that any wall construction of carbon raises the latter above the slag line and would result in probable burning and destruction of 100 the same.

The slag from the furnace is discharged through the usual outlet 36.

A lower header 37 may also be employed in the 105 boiler construction.

With this improved construction it will be manifest that the bottom will be free and detached from the walls of the furnace and at the same time the space between the bottom and the walls will be sealed against the escape of 110 gases.

Furthermore, by this arrangement the bottom of the furnace may be raised or lowered according to the construction of the furnace and as 115 desired.

While the preferred form of the invention has been herein shown and described, it is to be understood that various changes may be made in the details of construction and in the combination and arrangement of the several parts, 120 within the scope of the claims, without departing from the spirit of this invention.

What is claimed as new is:—

1. In a furnace of the character described, a bottom independent of and disconnected from 125 the furnace walls, whereby said bottom will be free to expand and contract independently of the furnace walls and the latter will be relieved of any strain caused by such contraction and expansion of the bottom, means forming a seal 130 between the bottom and the furnace walls, said bottom comprising a shell, a hearth, means forming a cooling liquid circulation space about the hearth, means forming a cushion between said cooling space forming means and said shell, 135 and means for circulating cooling liquid through said space.

2. In a furnace of the character described a bottom separate and detached from the furnace wall, said bottom including a supporting plate, 140 a hearth supported thereby, said hearth comprising a layer of insulating material resting upon the said plate, a layer of refractory material superposed upon said insulating material, a layer of carbon blocks supported upon said refractory material, and a continuous upright liquid cooled wall extending about said hearth.

3. In a furnace of the character described a bottom separate and detached from the furnace walls, a liquid seal between said bottom and the 150

5 said walls, said bottom comprising a hearth proper and a continuous upright liquid cooled wall extending about the hearth said hearth comprising a bottom, a layer of insulating material thereupon, a layer of carbon blocks at the top of the hearth and a layer of refractory material intermediate said insulating material and said carbon blocks.

10 4. In a furnace of the character described, a bottom disposed within, disconnected from, and spaced with respect to the walls of the furnace whereby the bottom will be adapted for free expansion and contraction with respect to the furnace walls, said bottom comprising a hearth, 15 means forming a cooling liquid circulation space about the hearth, an encompassing shell, means for circulating a cooling liquid through said space, a cushion between said shell and said cooling space forming means, and means forming a liquid seal for the space between the said bottom and the furnace walls.

20 5. In a furnace of the character described, a bottom disposed within, disconnected from, and spaced with respect to the walls of the furnace 25 whereby the bottom will be adapted for free expansion and contraction with respect to the furnace walls, said bottom comprising a hearth, means forming a cooling liquid circulation space about the hearth and an encompassing shell, all 30 separate from the furnace walls, means for circulating a cooling liquid through said space, said shell being spaced from said cooling liquid space forming means, a cushion between said shell and said cooling space forming means, means 35 forming a liquid seal for the space between the said bottom and the furnace walls, an inclined wall disposed above and about the periphery of said bottom, the said inclined wall resting upon the said shell and cooling liquid space forming 40 means and extending over and forming a protection for said cushion, and means for circulating a cooling fluid through the body of said inclined wall.

45 6. In a furnace of the character described, a bottom disposed within, disconnected from, and spaced with respect to the walls of the furnace whereby the bottom will be adapted for free expansion and contraction with respect to the furnace walls, said bottom comprising a hearth, 50 means forming a cooling liquid circulation space about the hearth and an encompassing shell, means for circulating a cooling liquid through said space, said shell being spaced from said cooling liquid space forming means, a cushion 55 between said shell and said cooling space forming means, means forming a liquid seal for the space between the said bottom and the furnace walls, an inclined wall disposed above and supported by said shell, and an additional inclined 60 wall supported by the furnace wall, said additional wall being disposed above and projecting over the upper edge of the first recited inclined wall.

65 7. In a furnace of the character described, a bottom disposed within, disconnected from, and spaced with respect to the walls of the furnace

whereby the bottom will be adapted for free expansion and contraction with respect to the furnace walls, said bottom comprising a hearth means forming a cooling liquid circulation space about the hearth, and an encompassing shell, all 80 separate from the furnace walls, means for circulating a cooling liquid through said space, said shell being spaced from said cooling liquid space forming means, a cushion between said shell and said cooling space forming means, means forming a liquid seal for the space between the said bottom and the furnace walls, an inclined wall disposed above and supported by said shell, an additional inclined wall supported by the furnace walls, said additional wall being disposed above and projecting over the upper edge of the first recited inclined wall, and means whereby a cooling fluid may be circulated through said additional inclined wall.

85 8. In a furnace of the character described, a bottom disposed within, disconnected from, and spaced with respect to the walls of the furnace whereby the bottom will be adapted for free expansion and contraction with respect to the furnace walls, said bottom comprising a hearth, 90 means forming a cooling liquid circulation space about the hearth, and a shell encompassing the bottom, all separate from the furnace walls, means for circulating a cooling liquid through said space, said shell being spaced from said cooling liquid space forming means, a cushion between said shell and said cooling space forming means, means forming a liquid seal for the space between the said bottom and the furnace walls, an inclined wall disposed above and about the periphery of said bottom, the said inclined wall resting upon the said shell and cooling liquid space forming means and extending over and forming a protection for said cushion, and means for circulating a cooling fluid through the body of said inclined wall, the cooling liquid flowing successively through said cooling space, inclined wall, and into the water seal.

100 9. In a furnace of the character described, a bottom disposed within, disconnected from and spaced with respect to the walls of the furnace whereby the bottom will be adapted for free expansion and contraction with respect to the furnace walls, said bottom comprising a hearth, 105 means forming a cooling liquid circulation space about the hearth and separate from the furnace walls, an encompassing shell separate from the furnace walls and spaced from said cooling liquid space forming means, a cushion between 110 said shell and said cooling liquid space forming means, means for circulating a cooling liquid through said cooling space, means forming a liquid seal for the space between the said bottom and the furnace walls, and an inclined wall disposed above and about the periphery of said bottom, the said inclined wall resting upon the said shell and cooling liquid space forming means and extending over and forming a protection for said cushion.

115 ARTHUR J. BOYNTON.
